UNITED STATES PATENT OFFICE

93,962

DESIGN FOR A SHOE

Benjamin Benjamin, New York, N. Y.

Application May 24, 1934, Serial No. 51,901

Term of patent 3½ years

To all whom it may concern:

Be it known that I, BENJAMIN BENJAMIN, a citizen of the United States, and resident of New York city, in the county of Kings and State of New York, have invented a new, original, and ornamental Design for a Shoe, of which the following is a specification, reference being had to the accompanying drawing forming part thereof, in which,

Fig. 1 is a plan view of a shoe showing my new design;

Fig. 2 is a side perspective view of the shoe;
Fig. 3 is a front view of the bow only.

The dominant features of the design as applied to a shoe in the form of a pump reside in the bands of suitable material secured to the pump

near the edges of the sole and extended upwardly around the sides of the shoe to the instep-engaging portion of the pump, and the bow of the same material with the loops and ends at opposite sides of the knot spread out and arranged so that one tip of each wing formed by a loop and end extends downwardly and along the side of the shoe towards the tip of the toe and the other tip extends upwardly to a suitable distance above the upper edge of the pump upper.

I claim:

The ornamental design for a shoe as shown and described.

Dated, May 21, 1934.

BENJAMIN BENJAMIN.
